CLARENCE E. BEACH, OF BINGHAMTON, NEW YORK, ASSIGNOR TO GEORGE O. KNAPP,
OF NEW YORK, N. Y.

SIGNALING MECHANISM.

1,078,984.

Specification of Letters Patent.

Patented Nov. 18, 1913.

Application filed June 4, 1912. Serial No. 701,696.

To all whom it may concern:

Be it known that I, CLARENCE E. BEACH, residing at Binghamton, in the county of Broome and State of New York, have invented new and useful Improvements in Signaling Mechanism, of which the following is a specification.

My invention relates to signaling mechanism, particularly to signal formulating and controlling mechanism for signaling apparatus such as fire alarm boxes.

In signaling apparatus such as fire alarm boxes the signal formulating mechanism usually comprises a signal wheel, circuit controlling springs, and signal levers coöperating with the teeth and notches on the signal wheel to control opening and closure of the springs, the teeth and notches on the signal wheel being arranged in accordance with a signal number as is well understood in the art. It is very desirable, in order to effectively control the signaling circuit and to prevent false signaling, that the contact springs act instantaneously when closing the circuit as well as when opening it. As the signal number of the boxes may have to be changed at times it is desirable that the construction be such that signal wheels representing any numbers may be interchangeably used in the box without requiring adjustment or reconstruction or replacing of the signal levers. In Patent No. 949,699 issued Feb. 15, 1910, to C. E. Beach and H. W. Doughty, an arrangement of signal controlling mechanism is illustrated in which two contact levers coöperate with a signal wheel to effect instantaneous make and break of the signaling circuit but in this arrangement if another signal wheel representing a different number is to be substituted it will require reconstruction of the signal levers or else the installation of different signal levers for coöperating with the new signal wheel. In Patent No. 621,093 issued March 14, 1899, to J. W. Johnson, is disclosed a signaling mechanism in which the signaling lever coöperates with a signal wheel and with circuit contacts, and in this arrangement a signaling wheel representing any number and of either the open or closed type, can be installed without requiring any change in the signaling lever. The defect, however, in the arrangement of this patent is that while the openings of the circuit will be instantaneous, the closures of the circuit

will be gradual and slow, and practice has demonstrated that with the arrangement of this patent, false signals are apt to be given.

One of the important objects of my invention is to produce improved construction and arrangement of signal formulating mechanism which will combine the desirable features of the two patents referred to, so that makes as well as breaks of the circuit will be instantaneous and so that one set of signaling levers or keys will be adaptable for efficient coöperation with signal wheels representing widely varying numbers, and whether of the open or the closed type.

Another object of the invention is to provide such improved construction for the signal wheel that adjustment can readily be made for timing the periods of closure.

Another object of my invention is to simplify the construction and cheapen the cost of manufacture of signal formulating mechanism arranged to produce makes as well as breaks of the circuit instantaneously by making the corresponding signaling levers of all boxes alike.

Another object of my invention is to produce improved construction and arrangement of signal formulating mechanism which will produce a maximum relative movement of the signaling contacts so as to provide a large break gap after each closure and yet be capable of being operated by means of a signal wheel of small diameter and having comparatively shallow notches.

Another object of my invention is to provide such construction and arrangement of signal formulating mechanism as will produce instantaneous action in closing a circuit and instantaneous action in breaking a circuit, and provide a large break gap after each closure upon the expenditure of a minimum amount of energy in driving the signal wheel.

The various features of my invention, both as to construction and operation are clearly illustrated on the accompanying sheet of drawings in which—

Figure 1 is a front elevational view of a frame-work supporting circuit controlling and signal formulating mechanism, together with a driving train therefor, Fig. 2 is a front elevational view of one part of the signal wheel mechanism and one of the signaling levers associated therewith, Fig. 3 is a front elevational view of the signal wheel mecha-

nism showing the parts in another relative position, Fig. 4 is a front elevational view of one part of the signaling wheel and its associated signaling lever and contact in relative position corresponding to that of Fig. 3, Fig. 5 is a view like Fig. 3 showing another relative position of the various parts, Fig. 6 is a view similar to Fig. 4 but showing the relative position corresponding with Fig. 5, Fig. 7 is a plan view of the upper contact spring, Fig. 8 is a plan view of the lower contact spring, Fig. 9 is a plan view of the signaling levers.

The frame-work 10 journals a shaft 12 carrying a hub 13 on which are mounted front and rear signal wheel parts 14 and 15. The power shaft 16 is connected with a driving spring 17 and carries a gear 18 which is connected through a suitable driving train 19 with the signal wheel shaft 12 in a manner well understood in the art. The front part 14 of the signal wheel structure has its periphery broken by notches *a* in accordance with the signal number, in this case 21, and the back signal wheel structure number 15 likewise has its periphery broken by notches *b* arranged in accordance with the signal number 21, the two signal wheel parts having a relative arrangement on supporting hub 13 which will be described later.

Pivoted on a stud 20 extending forwardly from the frame 10 are the front and rear signaling levers 21 and 22. The front signaling lever has a point 23 extending downwardly therefrom to coöperate with the teeth and notches of the front part 14 of the signal wheel, and the rear lever 22 has a point 24 extending downwardly therefrom for coöoperating with the teeth and notches of the rear part 15 of the signal wheel structure.

Mounted on the supporting frame 10 above the signaling levers is a block 24' of insulating material to whose lower side 45 is secured the contact spring 25 and to whose top is secured the contact spring 26. In Figs. 7 and 8 the form of these springs is plainly shown. The lower spring spreads at its end to provide a notch 27 and arms 28 and 28' for supporting contact points 29 and 29' respectively. The end of the upper spring 26 deflects downwardly and has its end 30 substantially parallel with the end of the lower spring and carries contact plates 31 and 31' for coöoperating with the contact points 29 and 29' on the lower spring. The front lever 21 has at its end the rear extension 32 supporting the vertical sleeve 33 in which is secured the stud 34 of insulating material. The rear signaling lever 22 has a front extension 35 at its end supporting the vertical sleeve 36 in which is secured a stud 37 of insulating material. The stud of the front signaling lever is shown as being a distance to the right of the stud on the

rear signaling lever and is adapted to extend through the slot 27 of the lower contact spring to coöperate with the upper contact spring. The contact stud 37 on the rear signaling lever coöperates with the lower 70 contact spring at the left of the slot 27 therein.

The front and rear parts of the signal wheel structure are relatively arranged so that the notches of the one will be substantially adjacent the solid portions or teeth of the other, the wheel shown being so arranged that when the point of either signaling lever is in a notch, the point of the other signaling lever will be on a tooth and during the 80 greater part of the signaling operation, the springs 26 and 25 will be held apart, even though the points carried by levers 21 and 22 are both supported by teeth, but the arrangement of teeth and notches may be varied in many combinations so long as the relation of notches and teeth is such that whenever the point of either lever drops from the tooth into a notch, the other lever will be supported by its point resting on 90 top of a tooth or be supported in a substantially elevated position through the engagement of its point 23 or 24 by the inclined advancing end of a tooth.

From the foregoing it will be seen that 95 if the arrangement of notches and teeth is such that both levers may simultaneously occupy their lower positions, both levers must then be raised before either should be allowed to fall; therefore much less energy 100 will be expended in securing the most efficient contacts and break gaps during the transmission of a signal, if the teeth and notches are so proportioned that whenever the movement of the signal wheel withdraws 105 a tooth from supporting the lever 22, the inclined advancing end of a tooth will have raised the lever 21 to a point where it will only permit the spring 26 to follow the downward movement of the spring 25 a very 110 slight distance, and the spring 25 will thereafter be raised into very close proximity to the spring 26 before spring 26 is released by the point 23 of the lever 21 falling into its next notch. When the contact springs 115 are entirely free of the signaling levers they will both be down and separated and when the signaling levers are associated with the springs the front lever will coöperate with the top spring and the rear signaling lever 120 will coöperate with the lower spring to effect instantaneous opening and closure of the springs. In Fig. 1 the mechanism is shown in normal position. The point of the front signaling lever is close to the crest of the first tooth *t*¹ of the front signal wheel part, while the point of the rear signaling lever is close to the trailing edge of the last tooth *t*² of the rear part of the signal wheel structure, the contact springs being closed. 130

When the box is started the signal wheel parts will rotate in the direction indicated by the arrow thereon. When the signal wheel starts to rotate the first tooth t^1 of the front part 14 is carried toward the point of the front signaling lever and this signaling lever is raised to carry its stud 34 closer to the end of the upper spring, but not into engagement therewith. While this is taking place the end of the last tooth t^1 of the rear part 15 of the signal wheel structure is being carried away from the point of the rear signaling lever and this signaling lever will drop just before the front lever reaches its uppermost position, and the lower spring 25 will drop. The upper spring normally held up by the lower spring will tend to follow the lower spring when the lower spring is thus released, but the stud of the front signaling lever, being directly below the upper spring, will receive this spring before it has traveled very far and when the downward movement of the upper spring is thus suddenly blocked the springs will be instantly separated and the circuit instantly broken, and we will then have the relative positions indicated in Fig. 3, and these conditions will be maintained as long as the point of the front signaling lever engages on tooth t^1 and the point of the rear signaling lever is riding on the bottom of the notch b^1 . Fig. 2 more clearly shows the normal position of the rear signaling lever, and Fig. 4 shows the position thereof and of the lower contact spring shortly after the box has started.

In Fig. 5 are shown the relative positions of the levers and springs just before the trailing end of the tooth t^1 reaches the point 23 of the front signaling lever and just before the top of the first tooth r^1 of the signal wheel rear part is brought under the point 24 of the rear signaling lever, the relative position of the signal wheel rear part and the associated signaling lever and spring being more clearly shown in Fig. 6. As soon as the incline at the leading end of the tooth r^1 engages with the point of the rear signaling lever this lever will be raised to carry its stud 37 into engagement with the lower spring 25 to carry this spring toward the upper contact spring held up by the front signaling lever and at about the time or just before the point 24 reaches the crest of the tooth r^1 the second notch a^2 of the signal wheel part 14 will come under the point of the front signaling lever and this signaling lever will suddenly drop, and the upper contact spring being thus released will immediately drop onto the lower contact spring which is being held in its uppermost position or is being just carried into its uppermost position by the tooth r^1 , so that the circuit controlled by the contact springs is instantly closed. This closed position of the

and rear levers are coöperating respectively with slot a^2 and the tooth r^1 and when the inclined advancing end of the tooth t^2 comes into engagement with the front controlling lever this lever will be raised to carry its stud 34 into position below the upper spring ready to block this spring when the lower spring is released as the point of the rear contact lever drops into the notch b^2 of the signal wheel part 15, this breaking operation being the same as took place when the first break was made. Thus directly precedent to each opening of the circuit the front signaling lever is in position to block the upper spring so that the lower spring may suddenly break the circuit, and directly before each closure the rear signaling lever is raised to bring the lower contact spring into position to receive the upper contact spring when the front signaling lever suddenly drops. The front part 14 of the signal wheel structure therefore controls by its notches the lengths of the closures, and by its teeth controls the blocking of the upper spring for the openings, while the back part 90 of the wheel structure controls the lengths of the openings by its notches, and by its teeth controls the blocking of the lower spring for the closures. It is evident that the lengths of the openings and closures may be controlled by the relative lengths of the various teeth and notches.

Fig. 2 illustrates substantially one prior art arrangement, as for example in the Johnson patent referred to. The signaling lever 22 whose vibration is controlled by the signal wheel part 15 will cause instantaneous opening of the contact springs but will effect only gradual closure thereof. In the arrangement shown in Fig. 2 the circuit would be closed between number groups and between rounds, but it is evident that by proper notching of the wheel the circuit could be caused to be open during these periods. In other words, either the closed or the open type wheel could be associated with the lever 22. In the arrangement of Fig. 1 the additional wheel part 14 and the additional contact lever 21 are provided, and the wheel parts could be properly notched to cause closure between number groups and between rounds instead of opening of the circuit during these periods, i. e., either the open or the closed type wheel structure could be used in connection with the controlling levers and the contact springs, and in either case the contact closure as well as the opening would be instantaneous. In practice the interval between the number groups and the interval between rounds bear a fixed relation to the unit interval, which unit interval is considered as comprising one signal tooth and one notch. For example, if in any wheel the unit interval were considered as 1, the interval between number groups may

be $2\frac{1}{2}$ and the interval between rounds may be $6\frac{1}{2}$, and in all the boxes connected in the line this relationship would be maintained. Where the box number is small, the signal teeth and the spaces between signal tooth groups and between rounds would be long. Where the box number is large, as for example 999, the signal teeth would be short and the distances between rounds would likewise be short. However, the periods of time during which these teeth or spaces would be effective is made uniform for the various boxes by adjusting the speed of the box running trains. The signal closures and the pauses between number groups and between rounds are thus of the same time duration in the various boxes. In the Beach and Doughty patent, already referred to, where two signaling levers are associated with a single signal wheel, the widths of the lever points control the length of the closed periods of the signal for any particular wheel, and it is apparent, that if a new wheel is to be substituted in a box, the signaling lever points must be correspondingly increased or decreased in width so that for every change in circuit wheels the levers must be changed or new levers installed. In my improved arrangement where two signal wheel parts, or their equivalents, are provided, so that each of the signaling levers will be controlled by a series of teeth and notches adapted to cause its proper vibration in relation to the other signaling lever the signal wheel may be adjusted for the proper length of closure periods, and one set of signaling levers will coöperate with signal wheel structures representing any numbers and of either the open or the closed type, and the closed interval may be arranged to represent any desired portion of the total interval from one stroke to the next. This is, of course, of decided commercial advantage for various reasons. With the old way, if the box number is to be changed it would be necessary to either ship the box back to the factory so that a new wheel could be applied and new signal levers installed or the old signaling levers changed, or it would be necessary to send new signaling levers and a new wheel to the user. The same would be true if the speed of the box was to be so altered as to make it desirable that the closed circuit intervals should bear a different relation to the interval between strokes of a signal in order to obtain the most efficient action of the magnets of non-interference devices and signal sounding or recording devices in circuit with the box. With my improved arrangement the user can employ signal wheels with different numbers or different relative periods of closure, to provide for all desired changes of speed or signal numbers, and can effect all such changes by merely taking out a given wheel structure

and applying the desired wheel structure in its place.

While I have shown circuit controlling springs constructed in accordance with the Patent No. 621,093 to Johnson, it is evident that in using my invention the circuit breaking contacts may be operated with equal efficiency if the contacts are of the form shown in Patent No. 949,699 to Doughty and Beach, or if any other usual or desirable form of circuit breaking contacts are employed.

The signal wheel structure of my invention can be of two parts suitably notched and then adjusted upon a supporting hub in the proper angular position, or the wheel can be of a single piece with the notches cut in at opposite sides thereof. Where the structure is of two parts, suitable indication should be provided on the parts so that the installer would have no trouble in applying the parts with the proper angular relation and in proper position in reference to the signaling lever points.

Modifications and changes are, of course, possible which will still come within the scope of my invention and I do not desire to be limited to the particular construction and arrangement shown and described herein and

I claim the following:

1. In signaling mechanism the combination of a signal member having two sets of teeth and notches and each set representing the same signal number, two signaling levers each coöoperating with one of said sets of teeth and notches to be actuated in accordance with the signal number, and circuit controlling contacts controlled by said levers to be alternately opened and closed instantaneously.

2. In signaling mechanism the combination of a signal wheel having teeth and notches about its periphery at one side thereof and teeth and notches about its periphery on the opposite side, the teeth and notches on each side being in accordance with the signal number and the teeth and notches on one side being offset relative to the teeth and notches on the other side, two signal levers each adapted for coöperation with the teeth and notches on one side of the wheel to be vibrated in accordance with the signal number, and circuit controlling contacts controlled conjointly by said levers to alternately open and close the circuit.

3. In signaling mechanism the combination of a signal wheel composed of two concentric sections each notched in accordance with the signal number, one of said sections being angularly off-set in relation to the other section, a signal lever for each section coöperating with the teeth and notches thereof, and circuit controlling contacts conjointly controlled by said levers.

4. In signaling mechanism the combination of a signal wheel comprising two concentric sections each notched and toothed in accordance with the signal number and one of said sections being off-set angularly relative to the other section so that the teeth of one section are opposite notches of the other section, two signal levers each co-operating with the teeth and notches of one section to be vibrated in accordance with the signal number, and circuit controlling contacts conjointly controlled by said vibrating levers to alternately and instantaneously open and close the circuit to be controlled thereby.

5. In signaling mechanism the combination of a signal wheel having teeth and notches along its periphery representing the signal number; contact springs, a transmitting member co-operating with said contact springs and with said teeth and notches, co-operation of said transmitting member with the teeth of said wheel causing closure of said springs and co-operation of said transmitting member with the notches of said wheel causing separation of said springs, both springs tending to move with said transmitting member upon co-operation of said member with the signal wheel notches, a second signal wheel having notches and teeth along its periphery to represent the signal number, a transmitting member for co-operating with the teeth and notches of said second signal wheel and for co-operating with one of said contact springs, said second transmitting member being adapted when in co-operation with teeth of the second signal wheel to block the movement of the associated contact spring upon release of the springs by the first transmitting member, and said second transmitting member serving when co-operating with notches of the second signal wheel to release its associated contact springs at a time when said contact springs are being moved toward each other by the first transmitting member.

6. In signaling mechanism the combination of a signal formulating member having two sets of teeth and notches, each set of 50 teeth and notches being spaced in accord-

ance with a signal number, two signal levers pivoted at a common point and each having a point for co-operating with a set of teeth and notches and substantially equidistant from the pivot point of said levers, each tooth having an inclined leading end and an abrupt trailing end and the trailing ends of the teeth of one set partly overlapping the abrupt ends of the teeth of the other set, and contact springs controlled conjointly by said levers to open and close a circuit to be controlled.

7. In signaling mechanism the combination of a signal member composed of two parallel sections each notched in accordance with the signal number, one of said sections being advanced in relation to the other section, a signal lever for each section co-operating therewith, and circuit controlling contacts conjointly controlled by said levers.

8. In signaling mechanism the combination of a signal member having two sets of teeth and notches, each representing the same signal number, two signaling levers simultaneously co-operating with said sections, and circuit controlling contacts conjointly controlled by said levers.

9. In signaling mechanism, a signal member, a set of teeth and notches in said member, the teeth of which set are arranged to represent the circuit closures and the notches circuit breaks of a signal, a second set of teeth and notches in said signal member, the teeth of said second set being arranged to represent circuit breaks and the notches circuit closures of the same signal, two signaling levers each co-operating with one of said sets of teeth and notches, a pair of contacts respectively controlled by said levers, said contacts being so constructed and arranged with relation to the signaling levers that the breaks and closures of the contacts will be formulated by the co-action of both sets of teeth and notches of the signal member.

In witness whereof, I heretunto subscribe my name, this 28th day of May A. D., 1912.

CLARENCE E. BEACH.
